UNITED STATES PATENT OFFICE

KNUT RUDY, OF NEW YORK, N. Y.

LAMP-BRACKET.

1,059,217.

Specification of Letters Patent. Patented Apr. 15, 1913.

Application filed August 31, 1912. Serial No. 718,088.

To all whom it may concern:

Be it known that I, KNUT RUDY, a subject of the King of Norway, residing at New York city, in the county of New York and 5 State of New York, have invented new and useful Improvements in Lamp-Brackets, of which the following is a specification.

This invention relates to electric light brackets and more particularly to an adjustable bracket of this sort used by dentists and others, requiring a lamp to be held in a certain adjusted position.

The object of the invention is to provide a simple and cheap device of this character 15 that may be readily attached to a wall or support and capable of wide adjustment to various degrees of angles.

To these ends the invention consists in the novel details of construction and combination of parts more fully hereinafter described and particularly pointed out in the 20 claims.

Referring to the accompanying drawings forming a part of this specification in which 25 like numerals designate like parts in all the views:—Figure 1 is a side elevational view of my improved bracket secured to a wall or other support. Fig. 2 is a cross sectional view taken on the line 2—2 of Fig. 1, and 30 Fig. 3 is a cross sectional view taken on the line 3—3 of Fig. 1.

Secured to a wall 1 or other support, are two oppositely disposed brackets 2 provided with bearing portions 3, within which are 35 adapted to be secured trunnions 4 for supporting a fitting 5, which fitting is provided with a segmental portion 6 having a segmental rack 7. Pivotaly connected by a pin 8 to the segment 6, is an arm 9, which 40 arm is provided at its inner end with a pawl 10 normally held in engagement with the segmental rack 7 by means of a spring 11, which spring bears at one end against a shoulder 12 on the pawl 10 and at its other 45 end against a shoulder 13 on the arm 9.

This arm 9 is adapted to be held and locked by means of the pawl 10, in various adjusted angular positions on the segment 6.

The pawl is released by means of a rod 14 50 pivotally connected as at 15, to a trigger 16, which trigger is pivotally connected as at 17 to the arm 9 and is adapted to be operated within the slot 18 cut on the lower portion of the arm 9. A fitting 19 is secured to the outer end of the arm 9 and is 55 provided with opposed bearings 20 within

which is pivotally held a tapering pin 21, provided at its lower end with a screw threaded portion 22 and at its upper end with an enlarged head or bearing portion 23. Fitted in this head or bearing portion 23 and adapted to be held at right angles to the tapering pin 21, is a pin 24 provided on one end with a socket 25 and on its other end with a screw threaded portion 26 on which is secured a clamp screw 27 provided with a handle 28, which screw is adapted to securely hold the tube 29 in any adjusted angular or universal position. The tube is also slidably mounted within the socket 25. On the outer end of the tube 29 is held a bushing 30 to the reduced end 31 of which is secured an electric lamp socket 32. The lamp cords or wires extend through the tube 29 and are connected to any suitable source of electric supply (not shown).

A spring 33 mounted within the tubular portion 34 of the vertical adjusting nut 35, is adapted to normally hold the tapering pin 21 carrying the lamp tube 39, in any adjusted horizontal position. The tension on this spring 33 is normally increased and diminished by the adjusting nut 35, as is clearly shown in Fig. 2.

From the foregoing it will be seen that 85 by the construction of a lamp bracket in accordance with my invention, persons such as a dentist or others, may be able to adjust an electric lamp in any convenient position, whereby they may be better able to perform 90 the duties pertaining to their occupation, to a better advantage than has heretofore been done.

It is obvious that those skilled in the art may vary the details of construction and 95 arrangements of parts without departing from the spirit of my invention and therefore I do not wish to be limited to such features except as may be required by the claims.

What is claimed as new is:

1. In an adjustable lamp bracket, the combination of a support, a segment pivotally mounted on the support and capable of horizontal adjustment, an arm pivotally connected at its inner end to the segment and capable of angular adjustment and a tube pivotally connected to the outer end of the arm and arranged for universal adjustment.

2. In an adjustable lamp bracket, the combination of a support, a segment pivotally mounted on the support and capable of hori-

horizontal adjustment, an arm pivotally connected at its inner end to the segment and capable of angular adjustment, means mounted on the arm and coacting with the segment for locking the said arm in an adjusted position, and a tube pivotally connected to the outer end of the arm and arranged for universal adjustment.

3. In an adjustable lamp bracket, the combination of a support, a segment pivotally mounted on the support and capable of horizontal adjustment, an arm pivotally connected at its inner end to the segment and capable of angular adjustment, means mounted on the arm and coacting with the segment for locking the said arm in an adjusted position, a tube pivotally connected to the outer end of the arm and arranged for universal adjustment, and means mounted

on the arm for holding the tube in an adjusted position substantially as described.

4. In an adjustable lamp bracket, the combination of a support, a segment mounted on the support, a segmental rack mounted on the segment, an arm pivotally connected at its inner end to the segment, a pawl mounted on the arm and arranged for coacting with the rack for holding the arm in an elevated position, a tube pivotally connected to the outer end of the arm, and means for holding the tube in any adjusted position.

In testimony whereof I affix my signature in presence of two witnesses.

KNUT RUDY.
